Primary Examiner — Abraham Bahta(74) *Attorney, Agent, or Firm* — Dinsmore & Shohl LLP(57) **CLAIM**

The ornamental design for a detergent pouch, as shown and described.

DESCRIPTION

FIG. 1 is a perspective view of the detergent pouch showing my new design;

FIG. 2 is a side view of the design of FIG. 1;

FIG. 3 is an end view of the design of FIG. 1;

FIG. 4 is a top view of the design of FIG. 1; and,

FIG. 5 is a bottom view of the design of FIG. 1.

The broken lines represent portions of the structure that form no part of the claim.
